UNITED STATES PATENT OFFICE.

JOHN A. ROMSPERT, OF DAYTON, OHIO.

DESIGN FOR A GAME-TABLE.

SPECIFICATION forming part of Design No. 31,377, dated August 8, 1899.

Application filed February 3, 1899. Serial No. 704,427. Term of patent 3½ years.

To all whom it may concern:

Be it known that I, JOHN A. ROMSPERT, a citizen of the United States, residing at Dayton, in the county of Montgomery and State 5 of Ohio, have invented and produced a certain new and useful Design for a Game-Table; and I do hereby declare that the following is a full, clear, and exact description of the invention, which will enable others skilled in 10 the art to which it appertains to make the same, reference being had to the accompanying drawings, and to the letters of reference marked thereon, which form a part of this specification.

15 In the drawings, Figure 1 is a plan view of my design; Fig. 2, a transverse section of Fig. 1, and Fig. 3 a longitudinal mid-sectional view of Fig. 1.

As shown in the drawings, the leading or 20 material feature of my design consists of an oblong rectangular table, the top side of which has two longitudinal gutters A' on the

outer sides and two similar gutters a' on the inner sides, between each two of which there is a bowling-alley B B. At one end of the 25 table there is a segmental concave C, with a circular opening D therein. The table A has an upturned rim B' around its edges and a longitudinal bead or division-strap E, separating the said table into two halves of uniform areas. At the opposite end of said table there is a box G. On the upper parts of the alleys B there are two series of circular designs comprising two triangular forms. 30

I claim—

The design for a game-table as herein shown and described.

In testimony that I claim the foregoing as my own I hereto affix my signature in presence of two witnesses.

JOHN A. ROMSPERT.

Witnesses:

WILLIAM POHLMANN,
R. J. McCARTY.
